(57) **CLAIM**

The ornamental design for an belt unit for an animal treadmill as shown and described.

DESCRIPTION

FIG. 1 is a perspective view of a belt unit for an animal treadmill showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 a partial enlarged view of portion 9 in FIG. 2;

FIG. 10 is a perspective view of a wheel hub of the belt unit for an animal treadmill showing my new design;

FIG. 11 is another perspective view thereof;

FIG. 12 is a front elevational view thereof;

FIG. 13 is a rear elevational view thereof;

FIG. 14 is a left side elevational view thereof;

FIG. 15 is a right side elevational view thereof;

FIG. 16 is a top plan view thereof;

FIG. 17 is a bottom plan view thereof;

FIG. 18 a partial enlarged view of portion 18 in FIG. 10;

FIG. 19 an assembled perspective view of the belt unit for an animal treadmill; and,

FIG. 20 a partial enlarged view of portion 20 in FIG. 19.

The dashed broken lines illustrate portions of the belt unit for an animal treadmill that form no part of the claimed design, and the dot-dash broken lines define the bounds of enlarged views and form no part of the claimed design.

1 Claim, 20 Drawing Sheets
